UNITED STATES PATENT OFFICE.

JOSEPH T. LEONARD, OF ST. CHARLES, MISSOURI.

HAIR-PIN.

1,102,155.

Specification of Letters Patent. Patented June 30, 1914.

Application filed September 19, 1913. Serial No. 790,812.

To all whom it may concern:

Be it known that I, JOSEPH T. LEONARD, a citizen of the United States, residing at St. Charles, in the county of St. Charles and State of Missouri, have invented certain new and useful Improvements in Hair-Pins, of which the following is a specification.

My invention relates to improvements in hair pins, the primary object being to provide an improved pin of this class with improved means for securing or anchoring the same in position when inserted in the hair thereby preventing disarrangement and retaining the same in proper position as against accidental loosening or loss.

A further object is to provide an improved hair pin of this class having its anchoring or securing parts so constructed, arranged, and disposed as to permit of the ready and convenient operation of the same in the anchoring or releasing movements without in any way interfering with the general convenience and efficiency of the hair pin as a whole.

With the above mentioned and other ends in view, the invention consists in the novel construction, arrangement, and combination of parts, hereinafter described, illustrated in some of its embodiments in the accompanying drawings, and particularly pointed out in the appended claims.

Referring to the drawings, forming a part of this specification Figure 1, is a plan view of a hair pin constructed in accordance with this invention, the anchoring members being detached. Fig. 2, a similar view of the complete hair pin, the anchoring members being in their closed position for retaining the pin after the latter is inserted. Fig. 3, a similar view of the same, the anchoring or securing members being in their open or retracted position preparatory to inserting the improved hair pin in or removing the same from the hair. Fig. 4, an enlarged side elevation of one of the improved anchoring or securing members removed. Fig. 5, a view of the outer or convex side of the same. Fig. 6, a view of the inner or concave side of the same. Fig. 7, a view of a modified form the anchor members being in their retracted position.

Similar numerals of reference designate like parts throughout all the figures of the drawings.

55 The improved hair pin comprises a pair of

pin members 1, terminating in and connected by a curved head or loop member 2, said loop head being preferably substantially semi-circular or ring shaped as shown.

As a means for anchoring or securing the improved pin when inserted in the hair, as well as providing convenient means for releasing the pin preparatory to the removal of the latter, anchor or spur members 3, are provided, said anchor members being of curved segmental form, and in the present instance, slidably mounted upon and connected to opposite portions of the head or loop 2, by means of sleeve portions forming guides, said anchors being oppositely arranged and being adapted to be stopped in their respective closed and open positions, as shown in Figs. 2 and 3 of the drawings, by the means hereinafter described.

As a means for resiliently holding or locking the anchor members in their respective closed and open positions, the sleeve portions of the anchors are each provided about their inner peripheries with struck out spring tongue members 3^a, (see Fig. 6,) adapted to ride upon and frictionally engage the inner periphery of the curved loop head 2, and to be seated in suitably formed and spaced notches 2^a, (see Fig. 1,) formed about the inner periphery of the loop head 2.

As a means for stopping the anchor members 3, in their proper closed or projected position as shown in Fig. 2, of the drawings, the lower portions of the sleeve members are cut away to form shouldered recesses 3^b, to receive and abut against the outer base portions of the pin members 1, and as a means for the convenient opening and closing of the anchor members 3, the latter may be provided with operating pins or studs 3^c.

In the modification shown in Fig. 7, of the drawings, the sleeve of the anchor member 3, are slightly extended so as to abut against each other at the rear central portion of the loop head 2, when the anchors are in their open or retracted position as shown, and the tongues 3^a, and operating studs 3^c, dispensed with, the sleeve portions of the anchors being adapted to snugly embrace the head loop and to be held in their respective open and closed positions by frictional contact.

From the foregoing description, taken in connection with the accompanying drawings, the operation and advantages of my invention will be readily understood.

Having thus described some of the embodiments of my invention, what I claim and desire to secure by Letters Patent, is,—

1. A hair pin, having a curved loop head 5 provided with stops, and segmental anchor sleeves slidably mounted on said loop head and provided with stops adapted to co-operate with said loop head and stops in stopping said segmental anchor sleeves in their 10 respective projected and retracted positions.

2. A hair pin, comprising pin members terminating in a substantially semi-circular shaped loop head provided with stop notches

about its inner periphery, and segmental sleeve anchors slidably mounted on said loop 15 head and provided with struck out tongue members adapted to be seated in said stop notches when said anchor sleeves are moved to their projected positions.

In testimony whereof I have affixed my 20 signature in presence of two witnesses.

JOSEPH T. LEONARD.
